UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,246,880.

Specification of Letters Patent. Patented Nov. 20, 1917.

Application filed February 3, 1912. Serial No. 658,115.

To all whom it may concern:

Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.

10 This invention relates to a semi-automatic computing head control of a type, useful in connection with such machines as the Underwood-Wright combined typewriting and computing machine.

15 The invention is an improvement on the devices disclosed in the pending applications Nos. 658,119 and 663,215 of Walter Wright.

An object of this invention is to provide a blank governing mechanism which can 20 be set up to obtain any desired sequence of predetermined combinations of states as to adding, subtracting and neutral of a plurality of computing heads.

A further object is to provide a governing 25 mechanism which after setting each computing head to act according to a certain state, will go over or beyond the adjusting point, so as to clear itself from the individual controlling mechanisms of each head, thereby leaving said controlling mechanisms free to change the state of each computing head from that determined by the governing mechanism, if desired.

In the embodiment used to show the accomplishment of these and other objects, 35 computing heads having actuatable elements such as master wheels and tens-carrying mechanisms, are controlled in their movement and direction of movement by clutches 40 which can be adjusted by shifting levers individual to each computing head, to one of three positions corresponding to adding, subtracting and neutral states of the accordant computing head.

45 The shifting levers which together with the clutches form individual controlling mechanisms for all the heads, are adjusted by shifters which are connected together to move in unison to form a governing mechanism. Each shifter is of a type such that 50 it can be set when sold, to give a predeter-

mined set of states of the computing heads according to the particular character of work desired by a buyer of the machine.

Two types of shifter are disclosed in this 55 case, one in which a pair of parallel disks having segments or tongues divided or marked out on the bdy of the disk by scis- sures, and originally lying in the same plane as the body or the disk, but capable of being 60 bent out to one of two positions, so as to adjust the shifting levers of the controlling mechanisms; one disk of each pair shifting the levers up to either one of two positions, according to the reach of the tongue, and 65 the other forcing the lever down to one of two positions.

In the other form of shifter shown, de- 70 tachable and interchangeable frusto-conical pegs may be screwed into any one of several openings in the similarly paired disks.

The shifters are connected to move in uni- 75 son by a shaft, and are operated by the depression of a key which rotates the shaft a fraction of a revolution in one direction, means being provided to render the return 80 movement of the key ineffective. The ex- tent of rotation of the shaft and thus of the governing mechanism at each depression of the key, is accurately determined by an over- 85 throw bar or lug which concomitantly limits the movement of the key and shaft.

In order that the operator may not neglect to actuate the governing mechanism every time, the bichrome attachment for 85 the ribbon shift of the typewriter is connected to the governing mechanism, so as to shift to red when the machine is sub- 90 tracting, so that the credit column will be written in red, whereby the operator will immediately notice by the change in color of the column of figures, if the governing mechanism has not been correctly operated.

Other features and advantages will be hereinafter described.

In the accompanying drawings, Figure 1 is a fragmentary side view in elevation with parts omitted to simplify the disclosure.

Fig. 2 is a fragmentary view in elevation 100 taken at right angles to the view shown in Fig. 1.

Fig. 3 is a detached vertical section through one of the computing heads, showing the relative arrangement of the parts thereof.

5 Fig. 4 is a horizontal section showing the actuator for rotating the governing mechanism shaft.

10 Fig. 5 is a skeleton perspective view of the governing mechanism, and showing its connection with the bichrome shift, whereby the color of the ribbon in typewriting can be concomitantly changed with the change in state of the computing heads.

15 Fig. 6 is a detail horizontal section showing the specific means for manipulating the bichrome shift from the governing mechanism.

20 Fig. 7 is a skeleton perspective view, showing the connection of one of the numeral keys to the valuating mechanism, whereby the extent of rotation of the master wheels is determined.

25 Fig. 8 is a fragmentary vertical section showing a modified form of shifting means.

Fig. 9 is a detail plan view showing another view of the form shown in Fig. 8.

Fig. 10 is a detail horizontal sectional view of the gearing for the tens-carrying mechanism.

30 Fig. 11 is a perspective view of one of the controlling disks, showing the same in the form of a blank.

Referring more particularly to the separate parts of the invention as embodied in 35 the form shown in the drawings, 1 indicates numeral keys, and 2, letter keys, which actuate through the intermediary of bell cranks 3, type-bars 4 to throw the latter against the front side of a platen 5 mounted 40 on a carriage 6, which in turn travels on one or more rails 7 under the control of an escapement mechanism indicated in general by the numeral 8.

Each of the numeral keys, as will be seen 45 by reference to Fig. 7, on being depressed, pulls down on a link 9 so as to rock a bell crank 10 drawing on a link 12 which is connected at its opposite end to swing a lever 13, so as to plunge one of a series of jacks 50 14 against one of a series of pins 15 loosely mounted in a valuating wheel 16.

The valuating wheel 16 is held against rotation by one of the pins 15 previously projected, being in engagement with an escapement wheel 17 secured to the same shaft 18 as another escapement wheel 19, which in turn is held from rotation by engaging with one of a pair of detent lugs 20 on a rock shaft 21. The rock shaft 21 is oscillated 55 at each depression of a numeral key 1 by means of a collar 22 which is actuated by all of the levers 13 which engage therewith, against the tension of a spring 23. The collar 22 in turn swings a lever 24 which is

connected to the rock shaft 21 through the intermediary of a link 25 and an arm 26 on the rock shaft 21.

The valuating wheel 16 when thus permitted to rotate, also in turn permits the rotation of a gear 27 mounted on the same shaft as the valuating wheel 16, which gear meshes with the gear 28 on a shaft 29 having at its front end a bevel gear 30. The bevel gear 30 is normally under a tendency to rotate, due to a drive from a motor 31 but is prevented by the valuating wheel 16 until a numeral key has been depressed, the rotation of the motor 31 in the meantime being taken up by a slip clutch, not shown. The bevel gear 30 is driven by the motor 31 through the intermediary of a slip clutch, not shown, and a shaft 32 which is connected to the motor by means of a pair of gears 33 and 34, and which is also connected to the bevel gear 30 by means of a bevel gear 35.

The bevel gear 30 also meshes on its opposite side with a bevel gear 36 on a shaft 37 having a bevel gear 38 meshing with a bevel gear 39 on a shaft 40. The shaft 40 is for the purpose of driving certain actuatable elements of a plurality of computing heads 41 and 42, which in this instance are the master wheels, one of which is indicated at 43 in Fig. 3.

Each of the master wheels 43 is splined onto a shaft 44, so that it can be rotated by the shaft 44 and yet is free to slide longitudinally through a series of computing wheels 45 arranged side by side coaxially with the shaft 44.

Each of these computing wheels 45 is provided with inwardly projecting teeth forming internal gears 46 which mesh with the master wheel 43. The computing wheels 45 are also provided with external teeth forming external gears 47 meshing with gears 48 carrying dial or numeral bearing wheels 49 which are adapted to successively exhibit the numerals thereon through an aperture 50 in the computing head casing 51.

Each of the master wheel shafts 44, as will be seen by reference to Figs. 1 and 2, are provided respectively in the case of the computing heads 41 and 42 with bevel gears 52 and 53 meshing with pairs of oppositely facing bevel gears loosely mounted on the shaft 40. These latter gears which are adapted to drive the master wheel shafts in either direction, are indicated by the numerals 54, 55, 56 and 57. Interposed between each pair of the bevel gears meshing with the bevel gears 52 and 53, there are provided clutches 58 and 59 splined onto the shaft 40, so as to be each shiftable into one of three positions corresponding to a connection of either one of a pair of gears in driven relation with the shaft 40, and with a position

corresponding with the disconnection of both gears of a pair from driven relation with the shaft 40.

It is essential in the type of computing head with which this invention is illustrated, to carry one complete rotation of a computing wheel of lower denomination to a computing wheel of next higher denomination. For this purpose, as will be seen by reference to Fig. 8, there is provided a tens-carrying mechanism indicated in general by the numeral 59, which forms no part of this invention, and so will not be specifically described, but depends for its operation on the rotation and direction of rotation of a roller 60 which is driven from a shaft 61 through the intermediary of a train of gearing indicated in general by the numeral 62.

There is one of these shafts 61 in the case 20 of each computing head, and they are both provided with bevel gears similar to the bevel gears 52 and 53, and are indicated in the case of the computing heads 41 and 42 respectively by the numerals 63 and 64. These bevel gears 63 and 64 also mesh with paired bevel gears loosely mounted on a shaft 65. The paired bevel gears are indicated by the numerals 66, 67, 68 and 69.

Interposed between each pair of bevel gears, there are provided clutches 70 and 71 which are splined on to the shaft 65, so as to be capable of being shifted to one of three positions corresponding to a disconnection of shaft 65 from driving the bevel gears 63 and 64 to a connection with either one of the pairs of bevel gears corresponding to the driving of the bevel gears 63 and 64 in opposite directions.

The shaft 65 likewise receives its drive 40 from the motor by being connected in driving relation with the shaft 32 through the intermediary of a shaft 72, which is connected to the shaft 65 by means of bevel gears 73 and 74, and to the shaft 32 by means of bevel gears 75 and 76.

The purpose of the clutches 57 and 58, 70 and 71, is to enable the state of the computing heads 41 and 42 to be controlled so as to either add, subtract, or remain neutral, 50 by controlling the drive and direction of drive of the master wheels and tens-carrying mechanisms. These clutches are shifted so that the change in drive of the master wheel and tens-carrying mechanism of each head is accomplished concomitantly, that is to say, the clutches 57 and 70 are shifted concomitantly by a composite lever 77, and the clutches 58 and 71 are shifted concomitantly by a composite lever 78. Each of the composite levers includes a main lever 79, which is pivotally mounted intermediate its ends as at 80, and is provided with a pin 81 engaging an annular groove in the associated clutch.

Each of the composite levers is also provided with a supplementary lever 82, having a pivotal engagement with the main lever 79 as at 83, and having a limited motion relative thereto, which is taken up by a spring 84.

The supplementary levers 82 are likewise connected to the clutches 70 and 71 by means of pins 85 engaging in annular grooves in the clutches 70 and 71. The composite levers together with the clutches, form controlling mechanisms which are individual to each computing head, and when shifted, determine the state of the associated computing head as to adding, subtracting, or remaining neutral.

In order that the individual controlling mechanisms may be adjusted concomitantly, so that all of the computing heads may have their state controlled at the same time and from a single point, there is provided a governing mechanism indicated in general by the numeral 86, which is shown to consist in this instance, of a shaft 87 having shifters 88 and 89 secured on the shaft in apposition to each of the controlling mechanisms for each of the computing heads.

For the purpose of rotating the shaft 87 and thus the shifters 88 and 89, there is provided a one-way clutch 90 which is adapted to connect in driving relation with the shaft 87, a gear 91. The one-way clutch 90 is shown to comprise a ratchet collar 92 secured to the shaft 87 and a ratchet collar 93 secured to the gear 91. The teeth of these ratchet collars face in opposite direction, so that the gear 91 can drive the shaft 87 when rotating in one direction, and will slip idly when rotating in the opposite direction.

To hold the parts of the one-way clutch 90 in engagement with each other, there is a spring 94 encircling the shaft 87, and bearing on the gear 91.

The gear 91 is in turn actuated by a pivotally mounted key lever 95, which is provided with a segment gear 96 engaging the gear 91. The normal method of actuating the key 95 is to depress the same, so that it will in turn rotate the gear 91, and thus rotate the shaft 87.

In order that the key may automatically return from its depressed position, there is provided a spring 97 which engages the under side of the key lever. For the purpose of obtaining a predetermined movement of the key 95, and also a predetermined rotation of the shaft 87, there is secured to the shaft 87 a locking ratchet wheel 98, which is engaged at the limit of throw of the key lever 95, as will be more readily understood by reference to Fig. 4, by a detent 99 secured rigidly to the key lever 95, and in fact formed integrally therewith.

The shifters 88 and 89 which are used to

- adjust the individual controlling mechanism for each head by manipulating the composite levers 77 and 78, are shown to be of two forms.
- 5 In the form shown in Figs. 1 to 7 inclusive, each shifter is shown to comprise a pair of spaced disks 100 and 101, secured to the shaft 87. Each of these disks when the machine is sold, has tongues 102 divided or marked out from the body of the disks by scissures, so that the salesman in setting up the machine for the buyer, can bend the tongues down from a position on a level with the body of the disk, to a projecting 10 position, such that it will come in engagement with one of the pins 103 and 104 secured respectively to the composite levers 77 and 78 of the computing heads 41 and 42.
- 15 The tongues 102 on the upper disk are projected downwardly toward the apposite face of the lower disk, and the tongues on the lower disk are projected upwardly toward the bottom face of the upper disk.
- 20 The tongues on each disk may adjust the associated composite levers to two positions corresponding to two states of the associated computing head. The disks when taken together control, with their tongues, the adjusting of the associated composite lever to 25 three positions corresponding to the three states of the accordant computing head.
- 25 In order to accomplish this, the ends of the tongues on each disk are bent out to either one of two positions at different distances from the body of the disk if they are bent out at all. By this arrangement, the pins 103 and 104 can be shifted backwardly and forwardly or not shifted at 30 each successive rotation of the shaft 87, due to the depression of the key lever 95.
- 35 Inasmuch as means are to be disclosed in this case for controlling the color of the ribbon of the typewriting mechanism from the governing mechanism, it would be well 40 to briefly describe the ribbon shifting mechanism at this point. As each of the type-bars 4 swings rearwardly to strike the platen 5, it comes into engagement with a universal bar 105, as will be more clearly 45 seen by reference to Fig. 5, so as to force the latter rearwardly, carrying with it an actuating frame 106 which carries slotted ears 109, 110, one of which will engage one of a pair of pins 107, located at different elevations on a pivotally mounted lever 108, so as to swing said lever different amounts, according to which of the pair of slotted 50 ears 109 and 110 is in engagement with the corresponding pin 107.
- 55 The lever 108 vibrates a shifter 111, which carries at its upper end a bi-colored ribbon 112, so as to swing the latter in front of the type on the type bars 4. This ribbon 112 is colored preferably red and

black, and the color which comes in front 65 of the type on the type bar will be determined by the position of the slotted ears 109 and 110 relative to the pins 107.

Ears 109 and 110 while connected to move rearwardly with the frame 106, are movable 70 transversely of said frame by means of a bar 113 which is connected to an arm 114 on a rock shaft 115.

In the ordinary operation of changing the color of the ribbon, the shaft 115 may be 75 rocked in one or the other direction by either one of a pair of keys 116 and 117 secured to the opposite ends of a lever 118 secured on the shaft 115.

To cause the oscillation of the shaft 115 80 to bring the red portion of the ribbon 112 up in front of the type on the actuated type bar when certain states of one or both of the computing heads are determined by the governing mechanism, there is provided on 85 the shaft 87 a collar 119, which carries one or more pins 120 located in register with such of the tongues as will shift the controlling mechanism to a position corresponding to the subtracting state of the accordant computing head. 90

Each of the pins 120, as will be seen by reference to Fig. 6, will come, during the rotation of the shaft 87, into contact with the end of a bell crank lever 121, so as to 95 rock the same and thereby shift a thrust lever 122 connected to the shaft 115 by means of an arm 123. This movement will cause the ear 110 to come into coöperation with the lower pin 107, so that the shifting 100 frame 106 will have a shorter leverage when actuated by one of the type bars 4, and thus move the shifter 111 farther up than normally, to bring the lower or red half of the ribbon 112 in front of the active type on the 105 type bars.

In the modified form of shifter shown in Figs. 8 and 9, each of the disks is provided with a plurality of openings located in spaced relation from each other, into which 110 may be detachably secured frusto-conical pegs 124 by having a screw-threaded reduced portion 125 engaging the screw-threaded openings which are indicated at 126. These pegs 124, as will be seen by reference to the full and dotted lines in Fig. 8, are of two heights, so that each shifting disk will be capable of controlling the movement of the composite levers 77 and 78 to 115 two positions; as in the case of the disks 120 100 and 101. The pegs 124 similarly to the tongues 102, project inwardly toward the apposite disk.

Whether the pegs or the tongues are 125 used, they are located at sufficient distances from each other to enable the pins 103 and 104 to occupy an entirely free space between them after they have been shifted by any

one of the tongues, so that the composite levers 77 and 78 will be free to move so as to control the state of the associated computing head after the governing mechanism has determined the state of said computing head. That is to say, the partial rotation of the shaft 87 is determined by the detent 99 to such an extent, and the position of the tongues 102 on the disks 101 relative to the shaft 87 is such, that each tongue in coming into engagement with one of the pins 103 or 104 will pass from a position free and clear of said pins through a position of contact with said pins, and after having adjusted said pins, will move to a position free and clear of said pins, permitting said pins and the connected levers to move independent of any movement of the governing mechanism including the shifters 20 with their flexed tongues.

Variations may be resorted to within the scope of the invention, and portions of the improvements may be used without others.

Having thus described my invention, I 25 claim:

1. The combination with a computing head, of a shifter for determining the state of said computing head comprising a shaft and a disk on said shaft, said disk having a 30 tongue projecting from one side thereof.

2. The combination with a computing head, of a shifter for determining the state of said computing head comprising a shaft and a disk on said shaft, said disk having 35 a tongue of variable effect projecting therefrom.

3. The combination with a computing head, of a shifter for determining the state of said computing head, including a disk 40 having a plurality of tongues bent to different distances from the body of the disk.

4. The combination with a computing head, of controlling mechanism for determining the state of said computing head, a 45 shifter for positioning said controlling mechanism including a pair of spaced disks with means projecting from apposite faces of said disks for engaging with said controlling mechanism.

5. The combination with a computing head, of controlling mechanism for determining the state of said computing head, a shifter for positioning said controlling mechanism including a pair of spaced disks 55 with means projecting from apposite faces of said disks for engaging with said controlling mechanism, and having tongues bendable from a position in the planes of said disks to projecting positions capable of 60 engagement with said controlling mechanism.

6. The combination with a computing head, of controlling mechanism for determining the state of said computing head, a

shifter for positioning said controlling 65 mechanism including a pair of spaced disks with means projecting from apposite faces of said disks for engaging with said controlling mechanism, and having tongues projecting toward the apposite disk to operate 70 said controlling mechanism.

7. The combination with a computing head, of controlling mechanism for determining the state of said computing head, a 75 shifter for positioning said controlling mechanism including a pair of spaced disks with means projecting from apposite faces of said disks for engaging with said controlling mechanism, and having tongues projecting toward the apposite disk to operate said 80 controlling mechanism, and arranged at spaced intervals sufficiently great to enable each of said tongues to clear said controlling mechanism after having adjusted the same. 85

8. The combination with a computing head, of controlling mechanism for determining the state of said computing head, a shifter for positioning said controlling 90 mechanism including a pair of spaced disks with means projecting from apposite faces of said disks for engaging with said controlling mechanism, and having tongues projecting toward the apposite disk to operate said controlling mechanism, and arranged at 95 spaced intervals sufficiently great to enable each of said tongues to clear said controlling mechanism after having adjusted the same, an actuator for moving said shifter, and means for determining the extent of movement of said shifter by said actuator. 100

9. The combination with a computing head, of controlling mechanism for determining the state of said computing head, a shifter for positioning said controlling 105 mechanism including a pair of spaced disks having tongues projecting toward the apposite disk in spaced relation to operate said controlling mechanism successively.

10. The combination with a computing 110 head, controlling mechanism for determining the state of said computing head, and governing means for successively adjusting said controlling mechanism to give a predetermined series of states of said computing head, acting to leave said controlling mechanism free from interference between each adjustment, so as to enable said controlling mechanism at any intermediate period, to be manipulated to some other state than 120 that determined by the last movement of said means.

11. The combination with a plurality of computing heads, of controlling mechanism individual to each computing head, a shifter for each controlling mechanism, a shaft for connecting said shifters to move in unison, a gear connected to said shaft, a key lever 125

- 6
- having a segment gear meshing with said first-mentioned gear, whereby said shaft may be rotated by said key lever, a ratchet wheel secured to said shaft, and a detent on said key lever engaging said ratchet wheel to stop the movement of said key lever and also to lock said shaft against further rotation.
12. The combination with a plurality of computing heads, of controlling mechanisms individual to each computing head, a shifter for each controlling mechanism, a shaft for joining said shifters to move in unison, a ratchet clutch on said shaft, a gear loosely mounted on said shaft, a ratchet clutch on said gear for connecting said gear in driving relation with said shaft while moving in one direction, and a key lever having a segment gear engaging said first-mentioned gear to rotate said shaft.
13. The combination with a plurality of computing heads, of controlling mechanisms individual to each computing head, a shifter for each controlling mechanism, a shaft for joining said shifters to move in unison, a ratchet clutch on said shaft, a gear loosely mounted on said shaft, a ratchet clutch on said gear for connecting said gear in driving relation with said shaft while moving in one direction, a key lever having a segment gear engaging said first-mentioned gear to rotate said shaft, and a spring for returning said key lever after having been actuated.
14. The combination with a computing head, of a controlling mechanism for governing the state of said computing head, a shifter for adjusting said controlling mechanism, a shaft for rotating said shifter, a gear loosely mounted on said shaft, a one-way clutch connection between said gear and said shaft, and a key lever having a segment gear meshing with said first-mentioned gear.
15. The combination with a computing head, of a controlling mechanism for governing the state of said computing head, a shifter for adjusting said controlling mechanism, a shaft for rotating said shifter, a locking ratchet on said shaft, means for rotating said shaft, and a detent brought into engagement with said ratchet after a predetermined rotation of said shaft.
16. The combination with a computing head, of a controlling mechanism for governing the state of said computing head, a shifter for adjusting said controlling mechanism, a shaft for rotating said shifter, a locking ratchet on said shaft, means for rotating said shaft, and a detent brought into engagement with said ratchet by the movement of a certain part of said means to stop the rotation of said shaft after a predetermined movement thereof.
17. The combination with a computing head, of controlling mechanism for governing the state of said computing head, a shifter for said controlling mechanism, a shaft for rotating said shifter, a pin connected to said shaft, means for rotating said shaft, ribbon mechanism, a chromatic shift for said ribbon mechanism, and connections whereby said chromatic shift may be operated by said pin.
18. The combination with a computing mechanism, of a shifter for governing the state of said computing mechanism, having a series of flexible members determining different states of said computing mechanism, said flexible members being bendable to change their position and thus change the state which they control.
19. The combination with a computing head, of governing mechanism for determining the state of said computing head, said governing mechanism including a disk having parts displaced from the face thereof to determine the character of control of said governing mechanism over said computing head.
20. In a computing machine, a state-controlling member for controlling the state of a computing mechanism as to addition, subtraction, or remaining neutral, comprising a blank in the form of a stamped disk having parts adapted to be displaced to determine the character of control to be exercised by said disk.
21. The combination with a computing mechanism, of a governing mechanism for affording different predetermined states of said computing mechanism, said governing mechanism including a metal sheet warped at different points to correspond with different states of said computing mechanism.
22. The combination with a typewriting mechanism including a bi-chrome mechanism for enabling the printing in a plurality of colors, of a computing mechanism, a governing mechanism for determining the states of said computing mechanism, means for operating said bi-chrome mechanism from said governing mechanism, to vary the color of printing with different states determined by said governing mechanism, and means for stopping said governing mechanism after an operation of said bi-chrome mechanism, in a position free and clear of said computing mechanism, so that said computing mechanism can be adjusted to a state other than that determined by said governing mechanism, for the particular color brought into play by said bi-chrome mechanism.
23. The combination with computing mechanism, of shifting means for controlling the state of said computing mechanism, and governing mechanism for said shifting means including a member having a plural-

ity of pliable tongues each forcibly adjustable to any one of a number of positions to determine predeterminedly a given series of states of said computing mechanism for a cycle of computing operations.

24. The combination with computing mechanism, of state-controlling means for said computing mechanism having a semi-rigid form to determine certain states of said

computing mechanism, and alterable as to 10 its controlling action of said computing mechanism by a forcible displacement of its parts.

GUSTAVE O. DEGENER.
